UNITED STATES PATENT OFFICE

GEORGE J. MEISEL AND BENJAMIN SKLEROV, OF NEW YORK, N. Y.

DESIGN FOR A BUCKLE

Application filed February 8, 1930. Serial No. 34,462. Term of patent 3½ years.

To all whom it may concern:

Be it known that we, GEORGE J. MEISEL and BENJAMIN SKLEROV, citizens of the United States, residing at New York, in the county of New York and in the State of New York, have invented a new, original, and ornamental Design for a Buckle, of which the following is a specification, reference being had to the accompanying drawing, forming part thereof.

Fig. 1 is a face view of a buckle, showing our new design.

Fig. 2 is a side view of the same.

We claim:

The ornamental design for a buckle, as shown.

In testimony whereof we have affixed our signatures.

GEORGE J. MEISEL.
BENJAMIN SKLEROV.
